UNITED STATES PATENT OFFICE.

JOSEPH M. SEDIVEC, OF MAY, IDAHO.

COTTER-PIN EXPANDER AND PULLER.

Application filed August 14, 1923. Serial No. 657,293.

To all whom it may concern:

Be it known that I, JOSEPH M. SEDIVEC, a citizen of the United States, residing at May, in the county of Lemhi and State of Idaho, have invented a new and useful Improvement in Cotter-Pin Expanders and Pullers, of which the following is a specification.

This invention relates to improvements in devices for expanding and pulling cotter pins.

The object is to provide a device of this character embodied in a single tool which may be readily handled by one hand and manipulated to spread or expand the split end of a cotter pin so as to retain the same in place, the device being readily introduced into active position and by the simple pressure of the hand, as in the operation of ordinary pliers, caused to function in the desired manner.

Another object is to provide a tool that may be easily and quickly applied in position for extracting or pulling the cotter pin from its position at the end of a bolt or elsewhere.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a side elevation of the improved cotter pin expander and puller; and

Figure 2 is a top plan view of the same.

The general formation and shape of the improved device is similar to an ordinary pair of pliers, such as are in common use, the principal difference residing in the fact that the pressure of the hand, in the present device, causes a separation of the active jaws, whereas, in the case of the pliers the reverse is true, the jaws of the same being caused to approach each other with more

or less force depending on the amount of pressure of the hand.

To secure this desired coaction of the jaws, the device comprises a pair of sinuously curved levers 1, each terminating, at one end in outwardly diverging, curved handles 2, having their outer surfaces rounded and knurled as at 3, so as to be readily grasped and operated by the thumb and fingers of one hand without injury thereto.

At an intermediate point of their lengths, the levers are reduced in thickness to provide opposite, interfitting recesses 4, which fit each other when the levers are placed in operative relation to each other, and thus provide a uniform thickness of the tool throughout its length, as shown in Figure 2 of the drawing.

Adjacent to the handle portions of the levers, each is provided with an enlarged, circular bearing disc or plate 5, having aligned perforations for the reception of a pivotal bolt 6, the said discs, as well as the opposite inner faces of the recesses 4 fitting flat against each other when the levers are operated.

Each lever, at its intermediate portion, where provided with the recess 4, is outwardly bowed and provided with a return bend, and the recessed bowed portions cross each other and terminate in elongated tapering jaws 7, which are of the full width of the levers and are in vertical alinement with each other, so that their opposed, flat inner surfaces 8 fit flat against each other in the same manner as the active jaws of an ordinary pair of pliers. It will be noted that the levers cross each other at two points, and at the first crossing point from the handles are fulcrumed together.

The lips 9 of the jaws are tapered down to a chisel edge extending the full width of the jaws, and are thus adapted to be readily introduced between the adjacent ends 10 of a cotter pin, as clearly shown in Figure 1 of the drawing; and it will be seen that by a pressure on the handles 2 to force the same towards each other, the jaws 7 are caused to separate, by reason of the double crossing of the levers, which brings about the forcing apart of the said ends 10 of the cotter pin to cause the same to be retained in its position.

A preferably U-shaped leaf spring 12 is located between the handles 2, with its bent

portion adjacent to the opposite discs 5 and the terminals of said spring located adjacent the ends of said handles, so that the tendency of the spring is to cause a separation of the handles, the result being to hold the jaws in contact with each other, so that no action of the hand of the operator is required to bring said jaws together for the purpose of introducing the lips 9 between the ends of the cotter pin.

An integrally formed hook 13 is formed on one of the jaws 7, at the thickest portion thereof, and may be utilized for engaging into the eye 14 of the cotter pin when it is desired to pull or extract the same from its position in the aperature of the bolt 11, such pulling action causing the spread ends of the cotter pin to be forced together sufficiently to permit the pin to be extracted.

In order to prevent the leaf spring 12 from becoming dislodged from its position between the levers, a rivet 15 is preferably applied to one of its terminals to secure the same to the adjacent inner face of the jaw.

From the foregoing it will be seen that a simple, cheaply manufactured, strong and durable device has been provided for applying and removing cotter pins, and which may be readily operated by one hand for the purpose, the entire gripping force of the hand being directed in a manner to force the ends of the said pins apart. It will be also seen that the hook 13 may be readily engaged in the eye of the cotter pin, the latter turned so that the lips of the jaws may bear against the nuts or some other adjacent part, when the device may be used in the manner of a lever of the first class to pull the cotter pin out of its seat.

What is claimed is:—

1. A cotter pin expanding device, comprising a pair of sinuously curved levers,

which cross each other at two points, handles at one end of the levers, spring means for separating the handles, means for pivoting the levers together at one of the crossing points, and flat tapering jaws provided at the ends of the levers remote from the handles, said jaws having opposed, flat inner faces which are held normally in contact by said spring means, the extremities of the jaws being tapered to an edge extending the full width of the jaws.

2. A cotter pin expander comprising a pair of intermediately fulcrumed levers having diverging handles at one end, a spring for normally separating said handles, said levers being outwardly bowed at one side of the fulcrum and having return bends terminating in elongated, tapered jaws having flat inner faces abutting each other, and chisel-edge lips, said levers each having interfitting recesses where they cross each other to provide a tool of uniform width.

3. A cotter pin expander and puller comprising a pair of intermediately fulcrumed levers having diverging handles at one end, a spring for normally separating said handles, said levers being outwardly bowed at one side of the fulcrum and having return bends terminating in elongated, tapered jaws having flat inner faces abutting each other, and chisel-edge lips, said levers each having interfitting recesses where they cross each other to provide a tool of uniform width, and one of said jaws having a longitudinally disposed hook to engage the eye of a cotter pin for extracting the same.

In testimony, that I claim the foregoing as my own, I have hereto affixed my signature.

JOSEPH M. SEDIVEC.
